US0D1109189S

(12) **United States Design Patent** (10) Patent No.: **US D1,109,189 S**
(45) Date of Patent: ** Jan. 13, 2026

(54) **DISPLAY SCREEN OR A PORTION THEREOF WITH A GRAPHICAL USER INTERFACE**

(71) Applicant: **KEMIN INDUSTRIES, INC.**, Des Moines, IA (US)

(72) Inventor: **Tiago Miranda Ribeiro**, São Paulo (BR)

(73) Assignee: **KEMIN INDUSTRIES, INC.**, Des Moines, IA (US)

(**) Term: **15 Years**

(21) Appl. No.: **29/886,531**

(22) Filed: **Mar. 9, 2023**

(51) LOC (15) Cl. **14-04**

(52) U.S. Cl.

USPC **D14/489**

(57) **CLAIM**

The ornamental design for a display screen or portion thereof with a graphical user interface, as shown and described.

DESCRIPTION

FIG. 1 is a front view of a display screen or portion thereof with a graphical user interface according to a first embodiment;

FIG. 2 is a front view of a display screen or portion thereof with a graphical user interface according to a second embodiment; and,

FIG. 3 is a front view of a display screen or portion thereof with a graphical user interface according to a third embodiment.

The broken lines showing the display screen or a portion thereof form no part of the claimed design. The remaining broken lines showing portions of the graphical user interface form no part of the claimed design.

1 Claim, 3 Drawing Sheets
